UNITED STATES PATENT OFFICE

141,571

DESIGN FOR A TIE RACK

Earl J. Coffed, Depew, N. Y.

Application April 26, 1945, Serial No. 119,235

Term of patent 14 years

(Cl. D33—8)

To all whom it may concern:

Be it known that I, Earl J. Coffed, a citizen of the United States, residing at Depew, in the county of Erie and State of New York, have invented a new, original, and ornamental Design for a Tie Rack, of which the following is a specification, reference being had to the accompanying drawing forming a part thereof.

Figure 1 is a side view of a tie rack embodying my design. Figure 2 is a front view thereof. Figure 3 is a perspective view of the same.

I claim:

The ornamental design for a tie rack, substantially as shown.

EARL J. COFFED.
